P. E. ROYSE,
Polishing Marble.
No 9,142. Patented July 20, 1852.

Fig. 3.

Fig. 2.

UNITED STATES PATENT OFFICE.

PLEASANT E. ROYSE, OF NEW ALBANY, INDIANA.

MACHINE FOR RUBBING STONE.

Specification of Letters Patent No. 9,142, dated July 20, 1852.

To all whom it may concern:

Be it known that I, PLEASANT E. ROYSE, of New Albany, in the county of Floyd and State of Indiana, have invented certain new and useful Improvements in Machinery for Rubbing and Polishing Marble and other Stone; and I do hereby declare that the following is a full, clear, and exact description of the same, reference being had to the accompanying drawings, forming part of this specification, in which—

Figure 1 is a top view or plan. Fig. 2 is an elevation looking in direction of the arrow Z Fig. 1, the part R being represented in section. Fig. 3 is a plan of the lower machinery taken as indicated by the line O O, Fig. 2.

The same letters of reference denote corresponding parts throughout the several figures.

To enable others skilled in the art to make and use my invention I will proceed fully to describe it.

A is the ground floor of a shop, or framing connected therewith, B an upper floor; or A and B may represent stages for carrying the combination of mechanical devices forming my invention.

The machinery situated between the floors 30 A and B is similar in appearance to that known by the name of "Fletcher's patent," but is an improvement thereon in construction and operation, as no rising and falling bed, requiring time and labor to adjust it, 35 is employed and rubbers having a more effective motion are adopted.

a, b, c, may represent slabs of marble or stone being operated on. They are arranged in any suitable number on the floor 40 or framing A, and sand leveled under and between them, they being situated as or in a similar manner to that shown in Fig. 3.

D is a fixed toothed wheel; E the revolving vertical driving shaft having attached 45 to it arms d e f g, the arm f serving by a continuation attached thereto for yoking cattle to drive the machine, or the shaft E may be operated, through band or gearing, by other power; a square framing, formed 50 by pieces h, i, j, k, is united to the arms d, e, f, g, and incloses the shaft E centrally within it.

G G are two of the rubbers (four of them being shown in the drawings); they are of 55 marble or stone, as may be, and serve by the friction of their lower faces to rub or polish

the slabs a, b, c, on which they rest, being so hung as to insure contact without rendering necessary (as in Fletcher's patented combination) packing up the slabs or bed, 60 the rubbers being made self adjusting by the manner in which they are hung or attached and operated and which is as follows: The rubbers G G are held in clamps or clasps C C formed of oblong or suitable shaped

framings between the sides of which the rubbers are held, the end pieces of either clamp lying over the top of the rubber which end pieces should be firmly secured to the one side of the clamp and pass loosely through

a mortise in the other for the purpose of packing up the loose side of the clamp against the edge of the rubber and accommodating different sized rubbers, the loose side of the clamp, when set, may be fixed

75 by wedges or screws or pins passing through or against it and the end pieces; the clamps C, C, thus holding the rubbers revolve together with the arms d e f g to which, on one side, they are linked by rods F F hanging loosely; the several rubbers, situated between the arms d e f g, I design to place or attach at various distances from the shaft

E for the purpose of operating on different widths or, numbers of slabs, and, by placing the one rubber at a greater distance from the shaft E than the adjoining or next rubber, the rubbing or polishing action will be improved as the face of the slab will have the rubbing motion on it varied by each rubber in succession, this effect being obtained

80 by the peculiar movement given to the rubber as will be evident from the continued description; the clamps C C, connected to the arms d e f g and revolving with them, 85 have also individual, or separate, motions given them through means of pinions H H, cranks I I, and connecting rods J J, the said pinions, by suitable connections, revolving

85 with the arms d e f g and having, in addition, a rotary motion of their own through the fixed wheel D into which they gear; the connecting rods J J are hung loosely, similar to the link rods F F, so as to admit

90 of vertical play in the rubbers which will 95 thereby not only adjust themselves to various thicknesses of stone being operated on, rendering an adjusting bed unnecessary, but, by the gravity of the rubbers being brought to bear on the face of the marble or stone,

100 the rubbing process will be simply efficaciously and expeditiously performed, the

105

110

115

action of the rubbers resembling more the hand process of scouring than is the case with other machines as will be evident from the foregoing description of parts and study 5 of the peculiar motion given the rubbers which, not only revolve with the arms *d e f g*, but, through the pinions *H H* operating cranks *I I* and connecting rods *J J*, together with the link rods *F F*—have a motion in and out from the center shaft *E*, not in a radial but in a winding, twisting or curvilinear direction more in unison, than a straight movement, with that adopted for scouring generally.

10 *S* is a tub or vessel for containing sand, it is seated on the arm *d* and through apertures in its bottom (regulated by slide or valve if required) serves to distribute sand, while a water cask *T* furnishes a supply of 15 water necessary in rubbing or polishing, and thus the time usually consumed in feeding the sand on by hand may be saved.

15 The revolving shaft *E* I propose to extend above the floor *B*, and through a toothed 20 wheel *K* to communicate motion to an ordinary rotary rubber *L* and blocking tables *M M*,—a pinion *k* (gearing into the wheel *K*) serving to operate the rubber *L* which turns within a fixed cylinder (having a cross 25 brace) wherein the stones to be rubbed are placed, as represented in Figs. 1 and 2, sand and water being supplied the rotary rubber which by the nature of its surface produces the necessary rub or polish on the stone resting by its own weight thereon. Stones being 30 blocked on the tables *M M*, are, as at present, operated on by slides *N N* having flannel faces coated with marble-putty the slides *N N* move as indicated by their respective 35 arrows Fig. 1, through means of cradles *P P* that rock to and fro, rods *l l* and *m m*, the latter rods being linked to an eccentric pin projecting from the face of a disk *Q* which is made to revolve by pinion on its 40 shaft gearing into the wheel *K*. The rotary rubber *L* also the blocking slides *N N* may be thrown out of or into gear by simply raising or lowering the pinions which operate them, this may be done through any suit-

able contrivance and will serve to reduce the 50 driving power and wear when one or both devices are not required to be used, a table *R* answers to carry the cylinder of the rotary rubber *L*. The combination of the rotary rubber *L*, blocking tables *M M* and 55 rubbers *G G*, all operating from one main shaft *E*, serve to make a very compact and convenient machine, as one driving power will serve to operate the three, while the machinery on the ground floor may be used 60 to rough rub only and the upper rubber and blocking tables for producing a smoother or finishing polish or for operating on small pieces of marble or stone exclusively.

I do not claim the separate employment 65 of a rotary rubber *L* and blocking tables *M M* as such are in common use, nor do I claim, of itself, giving the rubbers *G G* a separate motion, in addition to their revolving one, by means of pinions *H H* gearing 70 into a fixed wheel *D* and through cranks and connecting rods serving to operate the rubbers as such has before been done—but

What I do claim as my invention and desire to secure by Letters Patent is—

75 The combination of parts herein specified for rubbing and polishing marble or other stone, rubbers *G G* having, in addition to their revolving travel on the faces of the stones being rubbed or polished, a motion in 80 and out from the center shaft *E*, not in a radial, but in a winding, twisting or curvilinear direction produced by the cranks *I I* and rods *J J* and *F F* as shown and set forth, the said rubbers *G G* being held in 85 clamps *C C* so hung or connected as that the rubbers, by their weight, will adjust themselves to the stone without rendering it necessary to pack up the latter and for the further advantages specified.

90 In testimony whereof I have hereunto signed my name before two subscribing witnesses.

PLEASANT E. ROYSE.
